COMBINED SAFETY DEVICE AND RESETTING MECHANISM

Application filed May 15, 1925. Serial No. 30,578.

Our invention relates to fuel burning systems and more particularly to a fuel feed pump especially adapted for use in fuel burning systems.

5 While we shall describe our invention as being characterized mainly by the feature of a safety device associated with a motor driven pump which supplies liquid fuel to a tank or receptacle, the safety device being operable to bring about a stoppage of flow from the receptacle to the part to be supplied upon an excess rate of flow or upon a lowering 10 of the level in the receptacle, and in the instant case being related in its operation to 15 the operation of the pump in that it causes the pump to cease its automatic operation of continuously supplying fuel from the source of supply to the part to be supplied by stopping the feed to the receptacle, we 20 do not desire to be limited to the particular form of safety device, nor to its application in a pump to liquid fuel burning system, inasmuch as pumps of this type may be used elsewhere.

25 We find it desirable to drive a fuel feed pump for use in connection with fuel burners by means of an electric motor, or like source of power, due to the absence of vacuum pressure of an internal combustion engine which 30 is usually relied upon to operate fuel feed pumps when commonly used for feeding fuel to a carburetor of the engine. Consequently, in the operation of the pump, means must be employed to control the motor circuit according to some operating condition, which 35 means may comprise a float-controlled switch mechanism arranged to close the circuit when the liquid level in the pump falls below a predetermined point. It will be seen that the

40 operation of the pump is, therefore, automatic, and the pump will start pumping when the fuel therein reaches this predetermined level. It has been found, however, that the lowering of the fuel level is not always the 45 result of a normal operating condition, inasmuch as leaks might occur in the pipe-line between the pump and the burner. On the other hand, burners often cause an abnormal drain on the pump, when the needle valve of 50 the float mechanism therein fails to work.

If the float-controlled switch mechanism closes the circuit when the level drops in the pump, the latter will continue to pump until the level is restored. But when a leak occurs, as stated, or the burner places an over-load on the pump, this level will not be restored automatically and it is possible for the pump to empty the bulk supply tank before this condition will be observed. In the event of a leak, the possible conflagration 55 of the fuel emptied on the basement floor where the burner is located, is clearly apparent.

The primary object of our invention is to produce a fuel feed pump which will eliminate the above referred to difficulty of the prior art devices by the provision of a safety means of exceeding simplicity, which is certain and efficient in operation, and devoid of that delicate mechanism which is apt to require constant attention and frequent repair.

In carrying out our invention, we employ the aforesaid safety means preferably within a small receptacle, so that when substantially all the fuel is withdrawn from the receptacle, or withdrawn at a rate of flow in excess of a predetermined rate of flow as the case may be, the pump ceases its automatic operation of continuously supplying fuel to the receptacle. The normal controlling 75 means providing for normal automatic operation of the pump is to this extent disabled or rendered ineffective to continue its control over the continuous automatic operation of the pump and it cannot again normally 80 function until the safety means is rendered inoperative.

A further object of our invention is to provide an improved form of structure for serving as the aforesaid safety means, and we 85 prefer to have this structure assume the form of a float-controlled snap-over switch located in the bottom of the pump receptacle, which may have an action the reverse of the normal action of a float controlled snap-over 90 switch, namely, when the level rises, to close the motor circuit, and when the level lowers, to open the motor circuit.

In view of the foregoing explanation, however, the physical embodiment of the safety 100

means need not be limited to a float-controlled snap-over switch, inasmuch as other forms of safety devices may obviously be used to accomplish the same purpose, and, therefore, in view of our being the first to suggest such a safety control, we do not wish to be limited to any specific form, as long as the same end is to be obtained.

A still further object of our invention is to provide an improved resetting mechanism for the pump, so that, when totally emptied, the motor circuit may be temporarily closed to start the pump operating, in order to raise the fuel level therein and restore normal automatic operation of the entire system.

Further objects and advantages of our invention will be apparent from the following description when taken in connection with the accompanying drawings forming a part hereof.

In the drawings:

Figure 1 is a side elevational view in the form of a diagrammatic layout illustrating a fuel burning system embodying my improved fuel feed pump;

Fig. 2 is a vertical sectional view taken through the pump;

Fig. 3 is a cross-sectional view taken on line 3—3 of Fig. 2, looking in the direction of the arrows;

Fig. 4 is a top plan view of either of the upper two float-controlled switch units, it being remembered that the three switch units shown are similar, and that the lower unit is merely inverted so that this view is then a bottom view of the lower unit;

Fig. 5 is a bottom view of the two upper units, being a top view of the lower unit;

Fig. 6 is an enlarged sectional view taken on line 6—6 of Fig. 2; and

Fig. 7 is a detailed view illustrating the manner of electrically connecting the switch units in the motor circuit.

Referring to the drawings which illustrate the improved form of our invention, in Fig. 1 the fuel feed pump is generally designated as A, and comprises means for rendering the entire system, including the pump itself, inoperative to continue supplying fuel to the part to be supplied should a leak occur in the piping on the outlet side of this pump.

Our fuel feed system includes a bulk supply tank 10, a reserve supply tank 12, if so desired, a part to be supplied or burner 11 which may be equipped with a mixing chamber (not shown), into which the fuel is pumped by the fuel feed pump A, and which may include a needle valve controlled by a float mechanism for supplying fuel to the jet of the burner.

The pump A is in communication with the bulk supply tank 10 by means of a suction pipe 13. The fuel leaves the pump A by way of a pipe 14, which pipe 14 is in communication with burner 11. As long as a supply of fuel is in the bulk supply tank 10, pump A func-

tions to draw out the fuel and allow it to flow to burner 11. A reserve supply tank 12 is provided as a means of safety and as a warning to the owner of the building that the bulk supply tank 10 is empty, by containing a certain reserve of fuel for use during the time the bulk supply tank is being refilled. That is to say, if the pump A fails to draw out fuel from the bulk supply tank, the owner is given due notice to refill the tank 10, but is allowed the use of the reserve supply during that time to prevent the pipes in the building from freezing. A valve 15 may be employed normally to cut out the reserve tank 12. Valve 15 may be opened when the fuel in the reserve tank 12 is to be consumed, or the valve 15 may remain open at all times.

Pump A serves to operate automatically in supplying sufficient fuel to the burner 11. Feeding fuel to the burner from the pump is preferably accomplished by gravity, while the pump serves to automatically draw out fuel from the bulk supply tank 10 when the fuel level lowers below a predetermined point in the pump.

Pump A comprises a tank 20, a pump unit 21, and the mechanism in the receptacle 20 for controlling the operation of a rotary electric motor 22 for driving the pump unit 21, according to the liquid level in the receptacle 20; this latter mechanism comprising the essence of the present invention.

The pumping unit 21 comprises a bellows piston 24, having its lower end closed and its upper end rigidly fixed to plate 25 by means of soldered joints or other suitable fastenings. Piston 24 is preferably disposed within a cylinder 26, so that the fluid is adapted to be drawn into the chamber of this cylinder upon the up-stroke of the piston.

Liquid fuel enters the pump by way of suction pipe 13, which is in communication with a port 27. Associated with the piston chamber and receptacle 20 is an auxiliary chamber 28, constituting in reality a visible strainer 29, which, in addition, has the dual function of indicating a leakage in the suction pipe 13 and of serving as an air-receiver to absorb shocks in the line.

Fluid entering the chamber 28 will rise a certain distance and pass through a screen 30, and thence into a passage 31 by way of a port 32. By referring to Fig. 3, it will be noted that passage 31 communicates with a valve chamber 34, the intake of which is provided with a check valve 35, which permits a one-way flow of the liquid.

The outlet of the valve chamber 34 is in communication with the piston chamber of cylinder 26; the fluid when flowing into the chamber will be expelled, by expansion of piston 24 through a port 36, and into the receptacle 20 by way of a check valve 37.

Briefly the drive between the piston 24 and the motor 22 comprises a projecting member

38 connected to a shaft 39, on which shaft a worm gear 40 is disposed. Worm gear 40 is adapted to mesh with a worm 41 on the lower end of the motor shaft. It will be noted that the motor housing 23 is made integral with the base of the strainer 29, and that this motor housing serves as a closure for the upper end of the receptacle 20; furthermore, this motor housing serves as a closure for the cylinder 26, while the plate 25, carrying the cylinder 26 and the bellows-piston 24, serves as a connection between the motor housing and the receptacle 20.

Liquid fuel entering the receptacle 20 will rise to a predetermined level, which level is indicated at line A—B and is controlled by a float 45 operating a submerged snap-over switch 46, suitably arranged in the motor circuit.

We provide float 45 and snap-over switch 46 in the form of a detachable unit comprising a vertically depending support 48 which is provided at its upper end with a pair of lateral extensions 49 and at its lower end with a similar pair of lateral extensions 50. The support 48 is adapted to carry float 45 in a manner permitting vertical movement thereof. A pair of apertured lugs 51 are secured to the upper end of float 45. A yoke 52 is adapted to furnish a loose pivotal connection between the extensions 49 and the lugs 51, so that the resultant upward pressure of the fluid will permit the float to move vertically or parallel to the support 48. A similar connection is provided at the lower end of float 45, which connection comprises apertured lugs 53 receiving one side of yoke 54. A second yoke 55 is arranged to cooperate with the yoke 54 and to receive one end of a coil spring 56. The opposite end of spring 56 is fastened to yoke 54, and a contact lug 57 is carried by a terminal 74 connected in one side of the motor circuit. The opposite side of the circuit is connected through the frame 48 in a manner to be presently described.

Float 45 will tend to remain in its position during the initial movement of the liquid in receptacle 20, being arranged to move only when approximately the entire charge is pumped into the tank and the level has reached line A—B, so that the switch 46 operates with a snap-action. Assuming that the float is in its lower position, as illustrated in Fig. 2, spring 56 tends to draw the opposite ends of yoke members 54 and 55 together, but this movement is restricted by the lower side of the float 45 engaging the upper edges of lugs 50 and the yoke 55 engaging terminal lug 57. The resultant upward pressure of the fuel against the float is counteracted by the spring asserting a downward force until the level rises and this pressure is sufficient to overcome the force of the spring. In this manner, the fuel level approximately

reaches a level denoted by A—B in Fig. 2, before yokes 54 and 55 are biased beyond dead center. As soon as the yokes 54 and 55 are biased beyond dead center, the spring 56 acts in a reverse direction and accelerates the movement of the float. 70

More specifically, float 45 does not follow the fuel in its movement, but instead responds only when the fuel reaches the level A—B, when rising, or level C—D, when lowering. 75 Thus the snap-over switch is actuated suddenly with a quick make and break to open and close the motor circuit. With this arrangement the motor may be quickly started to actuate the pump for pumping the fuel into receptacle 20 from the bulk supply tank. Of course it is not necessary to provide a snap-over switch, or any other particular type of float-controlled switch in order to obtain the advantages of the present invention. 80 We have found that there is a possibility of the float-controlled switch 46 becoming disabled by sticking, or by the float 45 failing to move as the level of the fuel changes. If such a condition should occur, 85 and the switch is not closed, it is readily apparent that the pump will continue filling the receptacle 20 and cause the level to rise beyond the level denoted at A—B, in Fig. 2. 90 We have found it advantageous, however, 95 and less expensive to provide a second float-controlled switch mechanism 60 in the motor circuit above the switch 46, instead of providing an overflow pipe such as has been commonly employed in the past. Overflow 100 pipes are expensive, and a greater portion of them are made inaccessible due to the fact that Underwriters' requirements compel placing the pump supply tank under the ground outside the building. The overflow 105 pipes are then run under the ground, which makes it highly inconvenient to obtain access to them either for cleaning purposes or to repair leaks.

The overflow float-controlled mechanism 110 may be a substantial duplicate of the mechanism above described. It may also be supplied as a detachable unit having an electrically insulated connection to the base of pump cylinder 26. This connection may 115 comprise bolts 61 passing through the base of this cylinder and horizontal projections 62 which extend from the lateral extensions 49' of frame 48'. These bolts may be suitably insulated by means of insulation collars 120 63. The terminal 74' may be connected in this instance to the lead wire 65, comprising one side of the motor circuit. The opposite side of the motor circuit may be through the frame 48', this being accomplished by a connection 66 between the frames 48 and 48'. 125

Bolts 67 may pass through the projections 68 formed on the lower end of frame 48' and extensions 69 at the upper end of frame 48. This connection is not insulated, due to 130

the fact that it is desirable electrically to connect the frames 48 and 48'.

When the yoke 55' of the overflow float 60 is moved downwardly against the terminal contact 57', the circuit is closed through the frame 48' and said terminal contact 57'. When the level reaches the level denoted E—F in Fig. 2, the float immediately rises and breaks the motor circuit by withdrawing the yoke 55' away from the terminal contact 57'. Thus it will be noted that failure of the float 45 or switch mechanism 46 to operate will not permit the pump to continue pumping, due to the fact that float 60 is operative and breaks the motor circuit when the level reaches line E—F.

One of the important features of our invention is the provision of a safety device which in one of its specific physical forms 29 may be substantially the same type of float mechanism in the lower end of tank 20. However, this float mechanism, which I shall term the disabling float 70, is inverted so that the switch mechanism acts to open the circuit 25 when the float drops with the lowering of the fuel, instead of closing the circuits, as in the case of floats 45 and 60.

In Fig. 6 I have illustrated the relative arrangement of the switch mechanism controlled by all three floats. In the first two instances the switch mechanisms are below the float, or rather at the base of the frames carrying the floats, which switch mechanisms serve in reality as loose pivotal connections 35 between the lower end of the floats and the respective frames; while in the third instance the switch mechanism is at the upper end of the frame and also serves as a loose pivotal connection between the ends of float 70 and frame 48''. Here the yoke 52'' is at the base of the float 70, serving as a connection at this end with the frame 48''.

As illustrated in Fig. 6, the yoke member 55'', serving as one of the contact members 45 of switch 73, is pivoted in the lateral extensions 49'' and is adapted to make and break the circuit by contacting with the terminal lug 74''. Terminal lug 74'' is connected in circuit through a wire or strap 75, 50 which connects with the terminal 74 of switch 46. Frame 48'' may be carried by frame 48 by means of a connection 77, which is similar to the connection 66 between the frames 48 and 48', but is electrically insulated.

Connections 76 may comprise bolts 71 passing through horizontal extensions 78 and the frame 48'', and similar extensions 79 of frame 48.

It is desirable to insulate these frames and 60 accordingly we provide an insulation collar 76. The circuit is therefore through the strap 75 between terminals 74 and 74'' and the frame 48'' from where it continues through the wire 80 fastened to the frame at 65 81.

It will be observed, therefore, from the above description that the motor circuit may be traced first from the wire 65, terminal 74', yoke 55', and frame 48', connections 66 between the last frame and frame 48, yoke 55 70 contacting with terminal lug 74, strap 75, terminal lug 74'', yoke 55'' and then back by way of the wire 80. It will further be observed that such circuit connections place these switches in series with each other, and that the circuit may, therefore, be broken by opening any one of them. The upper two switches function to open the circuit by the rising movement of the fuel, while the bottom switch serves to open the circuit when 80 the fuel level lowers.

From the foregoing description it will be readily apparent that the appearance of a leak in pipe 14 will immediately cause the disabling float-controlled switch mechanism 73 to break the motor circuit and to thereby prevent a serious conflagration of fuel that may flood the basement floor 82. This arrangement is particularly unique in cases where an owner of a building may wish to leave the premises for several days and may then set the room thermostat (not shown) to maintain a certain temperature whereby to prevent the pipes of the house from freezing. Underwriters have found that it is during such periods of absence that leaks occurring in the pipes between the burner and the pump flood the basement and cause serious fires, because they usually go unnoticed too long.

The cause of many fires in buildings having fuel burning systems is traced directly to leaks of the character mentioned.

A further feature of our invention resides in the provision of a novel form of resetting mechanism for temporarily rendering the low level or disabling switch inoperative so that the motor circuit may be closed and the motor operated until the fuel has been brought to the normal level A—B. This resetting mechanism may be in the form of a push-button switch 75', suitably embodied in the motor housing 23, as illustrated in Fig. 3, and included in a circuit shunted around strap 75.

Switch 75' may be of the spring push-button type, whereby the owner may hold the switch closed until the normal level is reached. If he holds the switch closed too long the overflow float-control switch mechanism effectively opens the motor circuit. Thereupon the owner is informed that there is a sufficient quantity of fuel within the tank 20 to place the pump A in normal operating condition.

We wish to emphasize the fact that the feature of providing a tripping mechanism capable of rendering the pump inoperative to continue supplying liquid to tank 20, when an excessive demand is made at the outlet of 120 125 130

the tank, may take many forms other than that illustrated and described herein. As an example, it will be readily observed from the above description that a single float and switch may be used as a tripping mechanism for disabling the pump when this excessive demand is made, and also for opening and closing the motor circuit during the normal operation of the pump. This single float and switch has been disclosed in copending application Serial Number 85,370, filed February 1, 1926. Still further, the resetting mechanism may take the form of a mechanical means instead of electrical means as disclosed herein, and this change has been likewise shown in the copending application just mentioned. It will be quite obvious that the float 70 and its associated elements are normally inoperative and the normal control 20 is entirely regulated by the operation of the float 45 working between the levels A, B and C, D, respectively. Therefore, the rate of flow required to supply the burner or other part to be supplied may be completely and adequately maintained. If the rate of flow from the outlet 14 exceeds such requirements of the burner or part to be supplied, the float 70 operates its associated parts to cut off the feeding of fuel to the receptacle, thus preventing continued flow through said receptacle. It is, of course, to be understood that in the use of what we may term the consuming device, the level will automatically drop from level A, B to level C, D, whereupon the float 45 acts to again raise the level to the line A, C or in other words, to a predetermined normal level in the receptacle. This continues so long as the consuming device uses a normal quantity of fuel. When, however, the consuming device takes more than its normal demand, or for any other reason the quantity of fuel flowing out of the outlet 14 exceeds the predetermined rate, the normally inoperative float 70 through the instrumentality of its associated switch, stops the further or continued flow of fuel through the receptacle, notwithstanding the fact that the switch associated with the float 45 has been closed.

So far as our knowledge is concerned, we believe that we are the first to provide these improvements in a pump, and accordingly, will broadly claim the same.

We claim:

1. In a pumping apparatus, the combination of a pump having a receptacle for feeding liquid by gravity to a liquid consuming device, a connection between said receptacle and said device, and means for disabling the operation of said pump when the liquid drops below a predetermined low level in said receptacle.

2. In a pumping apparatus, the combination of a pump, a receptacle for receiving liquid supplied by said pump, a discharge

pipe connected to said receptacle, and means controlled by the rate of discharge of liquid in excess of or below the rate at which the liquid is supplied to said receptacle for disabling the operation of said pump. 70

3. In a pumping apparatus, the combination of a pump, a receptacle for receiving liquid supplied by said pump, a discharge pipe connected to said receptacle, and means disposed within said receptacle and controlled by the rate of discharge of liquid in excess of or below the rate at which the liquid is supplied to said receptacle for disabling the operation of said pump. 75

4. A pump comprising a receptacle and a pumping unit for supplying liquid thereto, and means within said receptacle for disabling the operation of said pumping unit when substantially all the liquid is withdrawn from said receptacle. 80

5. A pump comprising a receptacle and a pumping unit for supplying liquid thereto, and means connected to said pumping unit for disabling its operation when substantially all the liquid is withdrawn from said receptacle. 90

6. In a pumping apparatus system, the combination with an electrically operated pump, of a receptacle for receiving the fluid pumped, a discharge pipe connected thereto, and circuit controlling means associated with said pump for disabling the operation thereof when liquid is withdrawn by said discharge pipe at a rate in excess of the rate at which liquid is supplied by said pump. 95

7. A pumping apparatus comprising a receptacle, an electrically driven pumping unit for supplying liquid thereto, and means in circuit with said pumping unit for controlling the operation thereof, said means having mechanism for disabling the pump when liquid is withdrawn from said receptacle at a rate in excess of the rate at which liquid is supplied by said pumping unit. 105

8. A pumping apparatus comprising a receptacle, a motor driven pumping unit for supplying liquid thereto, and means disposed in said receptacle and in circuit with said motor for disabling said pumping unit when substantially all the liquid is withdrawn from said receptacle. 110

9. A pumping apparatus comprising a receptacle, a motor driven pumping unit for supplying liquid thereto, and a float controlled switch in circuit with said motor for disabling said pumping unit when the liquid is withdrawn from said receptacle at a rate in excess of the rate at which liquid is supplied by said pumping unit. 120

10. A pumping apparatus comprising a receptacle, a motor driven pumping unit for supplying liquid thereto, and a plurality of float controlled switch mechanisms in said motor circuit for disabling said pumping unit when supplying liquid either in excess of or 125

130

below the rate at which the liquid is withdrawn from said receptacle.

11. A pumping apparatus comprising a receptacle, a motor driven pumping unit for supplying liquid thereto, a float controlled switch for opening the motor circuit when substantially all the liquid is withdrawn from said receptacle, and a second float controlled switch for opening the motor circuit when a predetermined liquid level is attained in said receptacle.

12. In a pumping apparatus comprising a receptacle, and a motor driven pumping unit for supplying liquid thereto, the combination of three float controlled switches, the first for opening the motor circuit when substantially all the liquid is withdrawn from said receptacle, the second for opening the motor circuit when a normal predetermined liquid level is attained in said receptacle, and the third for opening the motor circuit at a higher level in the event said second switch fails to break said motor circuit when said predetermined level is reached.

13. In a pumping apparatus, a pump, a receptacle for receiving liquid supplied by said pump, means for disabling said pump when the liquid falls below a predetermined low level in said receptacle, and resetting mechanism for temporarily restoring the operation of said pump.

14. In pumping apparatus, a pump, a receptacle for receiving liquid supplied by said pump, controlling means providing for normal automatic operation of said pump, disabling means operable to render said controlling means ineffective to continue automatic operation of said pump when the discharge from said receptacle is in excess of a predetermined rate of flow, and means for rendering said disabling means inoperative.

15. In pumping apparatus, an electrically driven pump, a receptacle for receiving liquid supplied by said pump, a float controlled switch for disabling said pump, and means for temporarily by-passing said switch to restore the operation of said pump.

16. In pumping apparatus, an electrically driven pump, a receptacle for receiving liquid supplied by said pump, a float at the lower end of said receptacle, a switch controlled by said float, said float functioning to open said switch when substantially all the liquid is withdrawn from said receptacle, and means for by-passing said switch to operate said pump and refill said receptacle.

17. A pumping apparatus comprising an electrically driven pumping unit, a receptacle for receiving liquid delivered by said pumping unit, a switch in circuit with said pumping unit, and a float in said receptacle connected to open the circuit when in its lower position and to close the circuit when in its upper position.

18. A pump including a receptacle, a float

controlled mechanism for operating the pump in accordance with the quantity of liquid withdrawn from said receptacle, and means also operable in accordance with the quantity of liquid withdrawn from said receptacle for temporarily disabling the action of said float controlled mechanism.

19. A pump including a receptacle, a motor for driving said pump, a switch controlled by a float within said receptacle, and a second switch for temporarily by-passing said first switch.

20. A pump including a receptacle, a motor for actuating said pump, a switch, a float within said receptacle for operating said switch whereby said pump is automatically operated according to the quantity of liquid withdrawn from said receptacle, and a manually operated means for temporarily by-passing said switch.

21. A pumping apparatus for pumping liquid into a receptacle, provided with controlling means whereby the pump will be stopped when the liquid reaches a predetermined upper level, will be started when the liquid reaches a predetermined intermediate level and will be stopped when the liquid reaches a predetermined lower level.

22. Float actuated means for a pump, adapted to stop the pump when the liquid in the float chamber reaches an upper level, to start the pump when the liquid reaches an intermediate level, and to stop the pump when the liquid reaches a lower level.

23. In a float controlled liquid feeding apparatus, in combination with the float chamber, the float therein, and a control member adapted to be operated by the float at predetermined high and low levels of the liquid in the float chamber, an auxiliary control member adapted to be operated to stop the feed when the liquid falls below the said predetermined low level in the float chamber.

24. In a float controlled liquid feeding apparatus, in combination with the float chamber, the float therein, and a control member adapted to be operated by the float at predetermined high and low levels of the liquid in the float chamber, an auxiliary control member adapted to be operated to stop the feed when the liquid rises above the said high level in the float chamber.

25. In a float controlled liquid feeding apparatus, including a pump, a motor, an electric circuit for said motor, a float chamber, and a float adapted to control the opening and closing of said circuit at predetermined high and low levels of the liquid in said float chamber, and normally inoperative means for opening said circuit when the liquid in said float chamber falls below the said low level.

26. In a float controlled liquid feeding apparatus, including a pump, a motor, an electric circuit for said motor, a float cham-

ber, and a float adapted to control the opening and closing of said circuit at predetermined high and low levels of the liquid in said float chamber, and normally inoperative means for opening said circuit when the liquid in said float chamber rises above said high level.

27. In a float controlled liquid feeding apparatus, including a pump, a motor, an electric circuit for said motor, a float chamber, and a float adapted to control the opening and closing of said circuit at predetermined high and low levels of the liquid in said float chamber, and normally inoperative means for opening said circuit when the liquid in said float chamber falls below said low level and rises above said high level.

28. In a float controlled liquid feeding apparatus, including a pump, a motor, an electric circuit for said motor, a switch in said circuit, a float chamber and a float adapted to operate said switch at predetermined high and low levels of the liquid in said float chamber, a second normally closed switch in said electric circuit adapted to be operated to open said circuit when the liquid in said float chamber falls below the said low level.

29. In a float controlled liquid feeding apparatus, including a pump, a motor, an electric circuit for said motor, a switch in said circuit, a float chamber and a float adapted to operate said switch at predetermined high and low levels of the liquid in said float chamber, a second normally closed switch in said electric circuit adapted to be operated to open said circuit when the liquid in said float chamber rises above the said high level.

30. In a float controlled liquid feeding apparatus, including a pump, a motor, an electric circuit for said motor, a switch in said circuit, a float chamber and a float adapted to operate said switch at predetermined high and low levels of the liquid in said float chamber, a second normally closed switch in said electric circuit adapted to be operated to open said circuit when the liquid in said float chamber falls below the said low level and when it rises above the said high level.

31. In a float controlled liquid feeding apparatus, in combination with the float chamber, the float therein, and a control member adapted to be operated by the float at predetermined high and low levels of the liquid in the float chamber, a normally inoperative auxiliary control member, adapted when operated to stop the feed, and means actuated by the liquid in the float chamber for operating said auxiliary control upon a fall of the liquid in said float chamber below said low level.

32. In a float controlled liquid feeding apparatus, in combination with the float chamber, the float therein, and a control member adapted to be operated by the float at predetermined high and low levels of the liquid

in the float chamber, a normally inoperative auxiliary control member, adapted when operated to stop the feed, and means actuated by the liquid in the float chamber for operating said auxiliary control upon a rise of the liquid in said float chamber above said high level.

33. In a float controlled liquid feeding apparatus, in combination with the float chamber, the float therein, and a control member adapted to be operated by the float at predetermined high and low levels of the liquid in the float chamber, a normally inoperative auxiliary control member, adapted when operated to stop the feed, and means actuated by the liquid in the float chamber for operating said auxiliary control upon a rise of the liquid in the float chamber above the said high level and upon a fall of said liquid below said low level.

34. In a pumping apparatus, the combination of a receptacle, liquid feeding means for said receptacle, and means for controlling said liquid feeding means, including a float actuated means having connections with said liquid feeding means whereby said liquid feeding means is adapted to discontinue the feed of liquid when the liquid in said receptacle reaches an upper level, and to feed liquid when the liquid reaches an intermediate level, and means operably associated with said float actuated means whereby said liquid feeding means is adapted to discontinue the feed of liquid when the liquid reaches a lower level.

35. A pump apparatus comprising a motor driven pump, a tank associated with said pump for receiving the liquid pumped, a quick make and break switch mechanism for controlling the circuit of said motor driven pump, and float mechanism for controlling said switch mechanism whereby the switch mechanism will be open when the level of the liquid is at a predetermined high level and will be closed when the level of the liquid is at a predetermined low level, said mechanisms including provisions for again opening the switch mechanism when the level of the liquid is at a predetermined lower level.

36. In a float controlled liquid feeding apparatus, the combination with a float chamber, the float therein, a control member adapted to be operated by the float at predetermined high and low levels of the liquid in the float chamber to control the feed of liquid thereto, and a normally inoperative auxiliary control member adapted when operated to cause stopping of the feed, the operation of said auxiliary control member being controlled by the flow of liquid from said float chamber.

37. In a liquid supply system, a part to be supplied, a source of supply including a connection leading to said part and to a receptacle located above said part and receiv-

ing liquid to be fed to said part at a predetermined rate of flow, and means in said receptacle arranged for non-interference with said predetermined rate of flow but movable upon an excessive rate of flow to a position rendering it operable to bring about a stoppage of flow through the connection.

38. A fuel supply system comprising a source of supply, a part to be supplied, a connection from said source to said part, normally operative means providing for a flow of fuel through said connection at a predetermined rate to the part to be supplied and means arranged for non-interference with said predetermined rate of flow but movable upon an excessive rate of flow to a position rendering it operable to bring about a stoppage of flow through said connection.

39. A fuel supply system comprising a source of supply, a part to be supplied, a connection from said source to said part, normally operative means providing for a flow of fuel through said connection at a predetermined rate to the part to be supplied, means arranged for non-interference with said predetermined rate of flow but movable upon an excessive rate of flow to a position rendering it operable to bring about a stoppage of flow through said connection, and means whereby the normally inoperative means may be restored to the inoperative position upon resumption of flow at the predetermined rate.

40. A combination with a receptacle having float mechanism therein, of switch mechanism adapted to be actuated by said float mechanism, said float mechanism having operative connections with the switch mechanism, whereby the switch mechanism will be automatically moved to closed position when the float mechanism is at a predetermined point and the switch mechanism will be moved to open position if the float mechanism moves above or below said predetermined point, substantially as described.

In witness whereof we have hereunto subscribed our names.

GEORGE R. FOLDS.
LAWRENCE M. PERSONS.
